UNITED STATES PATENT OFFICE.

CLARENCE M. EVELETH, OF RIVER FOREST, ILLINOIS.

EXHIBITING MECHANISM.

1,096,360.

Specification of Letters Patent.

Patented May 12, 1914.

Application filed August 3, 1912. Serial No. 713,086.

To all whom it may concern:

Be it known that I, CLARENCE M. EVELETH, a citizen of the United States, residing at River Forest, in the county of Cook and State of Illinois, have invented a new and useful Exhibiting Mechanism, of which the following is a specification.

The present invention relates to improvements in exhibiting mechanisms, the primary object of the invention being the provision of a mechanism for automatically exhibiting one sign at a time, said signs being provided with indications upon two sides thereof and being displayed as a pendant and in an obstructed view by the mechanism, said mechanism being operably connected to means, whereby the pendant sign is removed and the next succeeding sign in a magazine is displayed, the removed sign being placed at the rear of and in the magazine to be again at the proper time exhibited.

A further object of the present invention is the provision of a novel sign exhibiting mechanism, which will operate with any number of signs, according to the size of the magazine, the same being provided with a novel form of removing and elevating mechanism, whereby the previously exhibited pendant sign is removed and placed at the rear and within the magazine while the first sign in the magazine is automatically released and placed in exhibiting position.

A still further object of the present invention is to provide a novel form of sign engaging mechanism carried by the elevating mechanism which after releasing a sign to be fed within the magazine will automatically engage the supporting portions of the pendant or exhibited sign, to be actuated at the proper time for removing the exhibited sign.

A still further object of the present invention is the provision of a mechanism which automatically, during the elevation of a pendant sign from exhibiting position, will release a single sign from the magazine and permit the same to slide by gravity to exhibiting position.

With the foregoing and other objects in view which will appear as the description proceeds, the invention resides in the combination and arrangement of parts and in the details of construction hereinafter described and claimed, it being understood that changes in the precise embodiment of the in-

vention herein disclosed can be made within the scope of what is claimed without departing from the spirit of the invention.

In the drawings—Figure 1 is a side elevation of the exhibiting mechanism with the casing removed, the parts of the mechanism being in the position assumed when exhibiting a sign, and just prior to the initial step in the elevation of the exhibited sign. Fig. 2 is a similar view with the sign elevating mechanism and releasing finger at their highest point and just prior to the releasing of a succeeding sign for exhibition. Fig. 3 is a similar view with the elevating arms at full length after having released a sign and previous to releasing the retarding fingers controlled by the elevator, dotted lines illustrating the position of the arms and sign during the elevation thereof and prior to the release of the sign. Fig. 4 is a similar view with the retarding fingers released and the sign entering the magazine, the elevating arms being moved downwardly to the next receiving position. Fig. 5 is a section through the machine, with the parts in the position they assume as shown in Fig. 3. Fig. 6 is a top plan view of the complete mechanism, with the casing removed, the elevating arms being in the position as shown in Fig. 3. Figs. 7 and 8 illustrate the side and top view of the operation of the elevating arms when moving downwardly to receive the exhibited sign. Fig. 9 is a diagrammatic view of the electrical circuit used to control the motor to operate the mechanism. Fig. 10 is a perspective view of one of the exhibits *per se*. Fig. 11 is a detached view of the clutch used to operatively connect the motor to the exhibiting mechanism.

Referring to the drawings, the numeral 1 designates the base of the machine and 2 the vertical standards, which support the top 3, thus providing a means whereby a casing (not shown) may encompass the entire top and standards and conceal the mechanism from view.

Main frame and magazine.—Secured to the base are the two forward uprights 4 and 4', the two intermediate and longer uprights 5 and 5', and the rear supporting brace 5^a to support at the proper incline, the two oppositely disposed plates 6 and 6' respectively. The upper edges *a* of the plates 6 and 6' constitute a guide for the reduced ends *S'* of the sign *S*, which when in maga-

zine position is disposed as shown in Fig. 1, at the forward ends of the plates 6 and 6'.

Connected to the plates 6 and 6' and bridging the same near the forward ends 5 and extending above the sign S within the magazine is a bridging plate 7, which carries the two rearwardly and upwardly extending curved sign guiding plates 8, whose free ends are supported by the transversely disposed bridging plates 9 whose terminals are connected to the outer faces of the respective plates 6 and 6' near the supporting standards 5 and 5'. The extreme ends 10 of the guiding plates 8 are bent downwardly at a point intermediate of the length of the plates 6 and 6', the purpose of which will presently appear.

The forward upper edges of the plates 6 and 6' are shouldered as at 11 and thus provide an abutting means for the reduced ends S' of the sign S to retain the forward sign in position in combination with the abutment 11' disposed at the forward edge of the base 1. By this means the signs S will all be disposed in parallel to each other and yet at an incline according to the inclination of the edge a of the plates 6 and 6' relatively to the base 1. The extreme forward ends 12 of the plates 6 and 6' respectively are projected 25 into the cut-away portion 13 of the base, such cut-away portion forming the outlet for the depending or pendant sign when in exhibiting position as clearly shown in Figs. 1 and 3.

35 *Sign feeding mechanism.*—The sign feeding mechanism, whereby one sign at a time is fed from engagement with the projections 11 of the plates 6 and 6' and down over the inclined edges b of the extensions 12, consists of the two levers 15 and 15' which are pivoted as at 14 and 14' to the respective vertical supports 5 and 5'. The free'ends 16 and 16' of the respective levers are disposed toward the rear of the machine, to be actuated as will later appear. In the forward ends 17 and 17' of the levers 15 and 15', are pivoted the sign extracting pawls 18 and 18', which are guided in their up and down movement by means of the pins 19 carried 45 by the vertical strips 4 and 4' of the supporting frame. The curved ends 20 of the pawls 18 and 18' are disposed when raised to engage the under edge of the respective reduced portion S' of the foremost sign S in the magazine, due to the depression of the free ends 16 and 16' of the levers 15 and 15', and thus elevate a single sign above the projections 11 and onto the inclined edges b, the retraction of the respective elevating pawls 55 18 and 18' releasing the kerfs 20 from the sign and permitting the sign to slide by gravity down over the inclined edges b and in front of the terminal 12' of the forward extensions 12 of the plates 6 and 6' respectively. In order to return the respective

arms 15 and 15' to their lowermost position, the spring 21 is connected to the base and to the free end 17 of each arm, and in order to hold the elevating pawls 18 and 18' in the position to engage the respective signs, the spring 22 is employed and is connected to its individual pawl and to one of the standards 5 or 5' of the frame. The pins 17' limit the downward movement of the arms 15 and 15'. 70

75 *Sign receiver and holder.*—The sign receiver and holder, as the pawls 18 and 18' are elevated to eject a sign at a time from the magazine is normally positioned, as shown in Fig. 2, so that as the reduced ends S' of the sign slide over the inclined edges 80 b, the sign will be moved from the position as shown in Fig. 2, to that shown in Fig. 3 without any perceptible jar. The mechanism for accomplishing this, consists of the two supporting brackets 23 and 23' which are carried by the base 1 and form a fulcrum for the two levers 24 and 24', each one of which is provided at its upstanding free end with the plates 25 and 25', respectively, to form a counter balancing means when the cross piece 26 constituting the sign carrying means is relieved of the weight of the sign S as will presently appear. The cross piece is provided with a plurality of plates 27 whose inwardly projecting prongs or hooks 85 28 are curved, and ride upon the forward edge of the projections 12 of the plates 6 and 6' and thus when the cross piece 26 is elevated to receive one of the signs, the same forms with the inclined edge b a continuation 90 thereof to permit of the easy removal of the sign from the inclined edges b into the receptacle formed by the respective prongs 28. In order to prevent any jar as the sign is delivered into the respective 95 hooks 28, the cushioning spring 29, one to each hook 28 and also connected to the cross piece 26, is disposed toward the free end 30 thereof in line with and between the body portion and the terminals of the respective 100 hooks 28. By this means the lugs S' will normally assume the position as shown in Fig. 3 with the said lugs S' at the rear of the free ends 30 of the cushioning springs 105 29. In order to prevent any undue swinging of the sign when in exhibiting position, the respective cushioning wires 30' are carried by the cross piece 26 and thus retain the pendant sign in a proper position and against swinging due to the delivery thereof within the elevating mechanism, or the jar of the vehicle carrying the exhibitor. In order to cushion the downward movement 110 of the arms 24 and 24' after having received the sign, the buffers 31 are positioned upon the base, as clearly shown in Fig. 6.

115 *Sign elevating mechanism.*—In order to remove the sign from the outer free ends of the arms 24 and 24' and return the pend- 120 125 130

ant sign to the magazine after the proper exhibition thereof and to make ready for the reception of the next succeeding sign to be exhibited, the two journals 32 and 32' 5 are carried by the base to the rear of and within the journals 23 and 23' and have disposed for rotation therein the transversely disposed shaft 33, which has keyed thereupon the gear wheel 34, which is normally 10 in engagement at all times with the teeth 35 of the rack bar 36. This rack bar 36 is pivotally connected, as at 37, to or near the lower free end of the main actuating lever 38. This actuating lever 38 is hingedly connected, as at 39, to a plate 40, said plate 40 being supported from the rear connecting bars 6^a of the plates 6 and 6'. Upon the inner face of the actuating lever 38 is the cam projection 41, while the lower free end 20 is engaged by a spring 42, which normally tends to move the actuating lever 38 toward the front of the machine or in the direction of the arrow as shown in Fig. 5. Two standards 43 and 43' are carried by the base 25 1 at the rear of the standards 32 and 32' and have journaled therein a shaft 44 which as shown in Fig. 5 carries an arm 45 with the anti-frictional roller 46 in the free end thereof. As this shaft 44 is rotated, as will 30 later appear, the free end of the lever 45 engages the actuating lever 38 and moves the same in opposition to the spring 42 so as to rotate through the gear 34, the shaft 33 as will later appear.

35 Carried upon the extreme ends of the shaft 44 outside of the journals 43 and 43', are the respective cams 47 and 47' which are disposed in operable relation to the free ends 16 and 16' of the sign projecting arms 40 15 and 15', the complete operation of which will be set forth later on.

Keyed upon the extreme end of the shaft 33 are the two arms 48 and 48', respectively, which are connected at their free ends by 45 means of the cross piece 49, said cross piece 49 being so positioned as to describe an arc of a circle to abut the spring terminals 30 of the cushioning springs 29 carried by the cross piece 26 of the sign receiving and holding mechanism.

Connected to the extreme ends of the arms 48 and 48' are the downwardly extending strips 50 and 50', which carry the plates 51 and 51' respectively. Each one of these 55 plates 51 or 51' is provided with a guiding strip, which is provided with the forward slightly curved edge 52, the receptacle portion 53 and the releasing cleat 54. By this means when the arms 48-48' are moved 60 downwardly from the position shown in Fig. 3 to that shown in Figs. 1 and 7, the sign being in the hooks 28, the two edges 52, of the plates 51-51', abut the inner faces of the lugs S' of the pendant sign, and move 65 the sign against the tension of the springs

29 and toward the cross piece 26. As the top of the edges 52 pass below the lower edges of the lugs S', the springs 29 being released propel the lugs S', and the sign so that the lugs S' pass between the plates 51-51' and assume the position shown in Fig. 7. The receptacle portions 53 and the cleats 54, provide a means for retaining the lugs S' of the sign during its elevation from the position in Fig. 1 to the position shown in Figs. 2, 3 and 5, at which latter position the sign has been released from the kerf or cleat 54 and deposited upon the upper edges a of the plates 6 and 6'. 70 75

In order to guide the signs to permit them to fall upright upon the edges a of the plates 6 and 6' when the elevating mechanism is in the position, as shown in Figs. 3 and 5, the plates 51 and 51' carried by the cross piece 49 are provided with the plates 55 having 80 inturned ends 56 disposed to coöperate with the kerfs 54 and provide a space therebetween to permit of the lugs S' in an upright position to slide therethrough to be deposited upon the upper edges a of the plates 6 85 and 6'. 90

As there is a possibility of the signs when being deposited upon the upper edge of the plate 6 having one end to travel faster than the other end and thus tend to fall between the plates 6, the retarding arms 58 and 58' are provided and are pivotally connected at 57-57' to the upper end of the plates 6 and 6' respectively. The outer free ends 59-59' of the retarding arms 58-58' are 95 projected beyond the cross piece 6^a and are disposed to be engaged by the adjacent edge of the cross piece 49 of the arms 48-48', simultaneously with the releasing of the sign from the plates 51-51'. This action elevates the hooked ends 60-60' of the respective retarding arms 58-58' above the edges a of the plates 6-6' respectively, so that the reduced ends or lugs S' of the released sign S will assume the position, as shown in 100 Figs. 3 and 5 and be retained by said hooks 60-60' until the elevating arms 48-48' have again moved to release the free ends 59-59' of the arms 58-58'. It will be noted that the respective hooks 60-60' are 110 positioned at a point just beyond the terminals of the depending ends 10 of the elevating guides 8, and are so close to the inner faces of the respective plates 6 and 6' as to not interfere with the main portion of the 115 signs S, as the lower free end thereof is released from the elevating guides 8 and falls between the respective plates 6 and 6'. This slight retardation in the travel on the inclined edges a of the plates 6-6', prevents the sign from unduly swinging due to the freeing of the lower end thereof from the inclined ends 10 of the elevating plates 8 and the position of the plates 51-51' carried by 120 the arms 48-48'. 125

Motor and control mechanism.—The motor and control mechanism for the present apparatus is preferably actuated by electricity, although it is evident that the same 5 may be a spring motor and in fact any other means that will effectually operate the mechanism before described.

The gearing with the electric motor M depends entirely upon the speed of the motor, 10 and therefore the detail structure herein shown is provided more for illustration, but is one of the methods to be employed, and particularly where a high speed motor is used. It is evident that a low speed motor 15 may be employed, or that the speed of the motor may be reduced when found desirable by the placing of a resistance in the motor circuit. In the present instance, the main actuating gear 61 is keyed upon the 20 shaft 44 between the standards 43—43' and is controlled through the electric motor M by means of the clutch C, as clearly shown in detail in Fig. 16. As shown the motor shaft M' is reduced as at a² and has a gear 62 rotatably mounted upon the reduced portion 25 and carrying a clutch finger 63 which is disposed in the path to be engaged by the clutch finger c, carried by the sleeve c' slidably mounted upon the motor shaft M'. The 30 gear 62 meshes with a gear 64 mounted upon the short shaft 64', the gear 64 also having a smaller gear 65 which is in mesh at all times with the small gear 66, mounted upon the stub-shaft 67. The gear 66 is in mesh with 35 the gear 68 which carries a small gear 68', which is in mesh at all times with a larger or main operating gear 61. By this means it will be seen that when the clutch C is 40 thrown in, that motion will be transmitted to the large gear 64 and the shaft 44 through the medium of the train of gears connected to the shaft 62 and the other intermediate gearing of the shaft.

In order to simultaneously control the 45 actuation of the clutch C and also the electrical circuits controlling the motor M, the lever 69 of the clutch is properly mounted to the machine, a spring 70 being connected to the lever 69 to normally actuate the same 50 to throw the clutch C out of engagement. This actuation of the clutch C is accomplished through the medium of the link 71 which is connected to the bell crank lever 72, said bell crank lever 72 being pivoted at 55 73 and having its free end 74 in a position to be engaged by the cone-shaped core 75 of the solenoid 76. The other free end of the bell crank lever 72 is kerfed as at 72' and is disposed to register normally with the notch 60 d formed in the cam 61' carried upon the outer face of the operating gear 61. By this means when the solenoid 76 is energized, the bell crank lever is operated to release the 65 kerf 72' from the notch d of the cam 61', throwing in the clutch C and at the same

time establishing an electrical circuit through the motor M as will presently appear. This circuit remains closed during one full rotation of the gear 61 or until the notch d is again in the position to receive the kerf 72' of the bell crank lever 72, the spring 70 moving the parts so as to open the circuit to the motor M and throw out the clutch C. The energization of the solenoid 76 is only of sufficient duration to close the circuit to 75 the motor M and throw in the clutch C, and to free the end carrying the kerf 72' from the notch d of the cam 61', and would therefore, unless intercepted immediately return to the notch d and the machine would fail to 80 operate. To avoid its immediate return, the arm 200 is pivoted near the shaft 44 and carries the segmental plate 201, whose outer edge is beyond the edge of the cam 61', and the curve of which is concentric with the 85 cam 61'. The spring 202 holds the arm 200 toward the front of the machine or in the direction of the rotation of the gear 61 and cam 61', and provides a resilient switch to be engaged by the kerf 72' of the lever 72 until 90 the cam 61' has moved a distance greater than the notch d, at which time the kerf 72' is guided upon the cam 61' and is held in such position until the cam 61' has traveled one full revolution, at which time the kerf 95 72' having acted upon the segmental plate 201, to open the notch d, will be snapped into said notch d to halt the motor. As above explained, when the kerf 72' is again drawn from the notch d, the spring 202 100 through the arm 200, draws the segment to its normal position, thus instantly locking the kerf 72' from returning to the notch d.

Electrical control.—As clearly shown in Fig. 9, the electrical control for actuating the solenoid 76 and the motor M is shown, the diagram being the complete circuits for energizing the solenoid 76 and actuating the motor M, the circuit being controlled through a car carried mechanism and means 110 disposed in the path of the car. In the diagram the contact 77 is carried by the inner free end of the bell crank lever 72 and has led thereaway from the conductor 78 to the motor M, while led away from the motor M 115 is the conductor 76 which is connected to the batteries B or any other source of electrical energy, and led away from the battery B at the opposite side to the conductor 79 is a conductor 80 provided with the stationary point 81, which is disposed in the path to be engaged by the contact 77, so that when the lever 72 is operated due to the solenoid 76, the circuit is closed to include the motor M and remains energized as long as the cam 61' retains the lever 72 in such closed position, that is one full revolution of the gear 61.

In order to control the solenoid 76 automatically or manually as may be desired, a conductor 82 is led thereaway from and 130

through a closing switch 83, which is maintained closed during the entire time that the exhibiting mechanism is in use. Led from this switch is a conductor 84 which is connected to the source of electrical energy E, which has led thereaway from a conductor 85 to the automatic control switch 86 which is connected to the solenoid through the conductor 87.

10 In order to permit the actuation of the indicator manually by the motorman or conductor, the two switches 89 and 90 are employed and are bridged to the conductors 85 and 86 through the conductors 88 and 91, 15 as clearly shown, the same providing a means whereby the indicator may be operated manually by either the conductor or the motorman, or may be operated automatically through the switch 86, said switch being automatically controlled by a car carried mechanism and a mechanism disposed in the path of the traveling car.

Operation.—From the foregoing description, taken in connection with the drawings 25 the operation of the present invention is readily understood but briefly stated it is as follows: Pre-supposing the parts to be in the position as shown in Fig. 1, with the sign pendant and in exhibiting position, with the 30 elevating mechanism in engagement with the lugs S' of the pendant sign S, the trolley carried mechanism is actuated to energize the solenoid 76, such energization actuating the bell crank 72 to close the circuit 35 to the motor M and at the same time throw in the clutch C. As before stated, this energization of the electromagnet is sufficiently long to cause the lever 72 to have its kerf 72' thrown from engagement with the notch d 40 of the cam 61', said cam 61' holding the lever in circuit closing position for one full revolution of the main gear 61. The clutch C now being in and the motor actuated, the gear 61 will be rotated and consequently rotate the shaft 44, the sign ejector actuating 45 cams 47—47' and the sign elevating actuating arm 45. The free end of the arm 45 being brought into engagement with the actuating lever 38 will now pull upon the rack 50 bar 36 and rotate the shaft 33 through the medium of the gear 34 and consequently start the elevation of the arms 48—48' and the cross bar 49 of the elevating mechanism. As the sign disposed between the plates 51—51' 55 is removed from the arms 28 of the sign holding arms 24 and 24' and assumes the position as shown in Fig. 2, the cams 47—47' are placed in engagement with the free ends 16—16' of the ejector actuating levers 15— 60 15'. This movement will raise the pawls 18—18' and consequently cause their kerfs 20 to engage the reduced ends S' of the lowermost sign S in the magazine, elevating the same above and upon the incline b. Previous to this action, the weights 25 due to the

release of the pendant sign from the outer free end of the arms 24—24' has moved the receiving hooks 28 to the position, as shown in Fig. 2, so that the extreme ends thereof will be disposed in continuity with the curved edges b, so that the released sign due to the ejecting pawls 18—18' will be received in such hook 28 without any perceptible jar, said sign overcoming the weights 25 and causing the arms 24—24' to assume the position as shown in Fig. 3. By this means an exceedingly short interval between the release or removal of a pendant sign and the reception of the next sign will be the result. The continued action of the lever 38, due to the arm 45, will cause the elevating arms 48—48' to move from the position as shown in Fig. 2, dragging the signs S over the guides 8 until the free edge thereof will ride downwardly upon the inclined terminals 10 of said plates 8 and be caused to fall downwardly between the plates 6 and 6'. The continued movement of the arms 48—48' and the cross plate 49 toward the rear of the machine, and just prior to the position as shown in Fig. 3, will present the lugs S' in the plates 51—51', so that the said lugs will be received in the kerf 54 of the plates 51—51' and as the cross piece 49 engages the free end 59 of the retarding levers 58—58', the sign will be released through the spaces between the cleats 54 and the extreme ends of the arms 55, where the same will be permitted to fall and engage the upper edges a of the respective plates 6 and 6', thus permitting the main portion of the sign S to bridge the space between the plates 6 and 6' and due to gravity slide downwardly to engage and be retarded in its movement by the lifted hooks 60 and 60'. The elevating arms 48—48' and the cross piece 49 are held in this position for an instant and until the lever 45 is moved upwardly about an angle of 90°, as shown in Fig. 5, and until the roller 46 becomes disengaged from the cam 41 of the actuating lever 38. At this moment the spring 42, which is normally exerting a tension in opposition to the lever 45 will move the rack bar 35 in an opposite direction, and thus rotate the shaft 33, which due to the spring 42 and the spring band connection 42', will impart a quick movement to the arms 48' and the cross piece 49, which moving in an opposite direction to that of elevating the sign will assume the position, as shown in Figs. 1 and 7 bringing the forward slightly curved edges 52 of the carrier down past and below the bottom edge of the sign lugs S', which owing to the action of the springs 29 are moved slightly back and thus place the extreme ends of the lugs S' of the pendant sign S within the receptacle formed by the inwardly bent edges 52 and 53 carried by the respective plates 51 and 51' of the extreme outer ends of the

elevating arms 48 and 48'. As the cross piece 49 is moved to release the free ends 59-59' of the retarding levers 58-58', the hooks 60-60' will be depressed below the edges *a* of the plates 6 and 6' and thus permit the pendant sign which has been momentarily halted in such position, to slide downwardly upon the edges *a* and resume its proper position within the magazine.

15 The clutch employed with the present invention has the knife-edge or pointed arms especially adapted for actuating a mechanism similar to the present one, and wherein neither part of the clutch is rotated and may 15 be thrown together, the respective engaging members of the clutch being so constructed as to render the movement to and from each other exceedingly smooth, so as not to jar the train of gears and the operating 20 mechanism of the sign. It is desirable that the bell crank lever 72, which operates the clutch, should have moved the clutch into engagement before the closure of the motor circuit, thus placing the clutch in engagement 25 with the motor shaft at a standstill.

With a mechanism, as herein set forth, it is evident that the same will be efficiently operated whether the car or vehicle is moving either slowly or rapidly, it simply being 30 necessary for the electromagnet 76 to be energized to actuate the bell crank lever 72, to release the same from the notch *d* of the cam 61', such release closing the motor circuit and at the same time actuating the 35 clutch and locking the clutch in engaged position so that the deenergization of the electromagnet 76 will in no way affect the operation of the motor, which is held energized until the main gear 61 has rotated one 40 full revolution and a complete train of operations in the exhibiting mechanism has taken place. The same may be said when the switch is controlled by the conductor or motorman, it simply being necessary for 45 either the motorman or conductor to close and open the switch to energize the electromagnet 76. It is also evident that with the mechanism herein set forth, that the pendant sign when in exhibiting position, said 50 sign being a double faced sign, is disposed below and exteriorly of the casing and preferably in the center of the car, so that the sign will be readily seen by the patrons and will never be obstructed from view by any 55 portion of the casing or exhibiting mechanism.

While herein is described the invention in detail, and is illustrated a combination embodying various features, which may at 60 times be used to advantage, it is not the desire or intention of claimant to be limited to the particular arrangement shown, or to an arrangement embodying the various auxiliary features, except as particularly 65 pointed out in the appended claims.

What is claimed is:

1. A sign exhibiting mechanism, having a casing, a weight actuated pivoted sign holding means mounted in the casing to be overbalanced by a sign, and to display the 70 sign below and exteriorly of the casing.

2. A sign exhibiting mechanism, having a casing, a weight actuated pivoted sign holding means mounted in the casing to be overbalanced by a sign, and to display the 75 sign below and exteriorly of the casing, and a sign elevating means disposed to remove the sign from the holding means for the next succeeding sign.

3. A sign exhibiting mechanism, having 80 a casing, a weight actuated pivoted sign holding means mounted in the casing to be overbalanced by a sign, and to display the sign below and exteriorly of the casing, a sign elevating means disposed to remove 85 the sign from the holding means for the next succeeding sign, a sign magazine, and means actuated simultaneously with the elevating means for releasing the succeeding sign from the magazine to deliver the same 90 to the holding means.

4. A sign exhibiting mechanism, having a casing, a weight actuated pivoted sign holding means mounted in the casing to be overbalanced by a sign, and to display 95 the sign below and exteriorly of the casing, a sign elevating means disposed to remove the sign from the holding means for the next succeeding sign, a sign magazine, and means actuated simultaneously with the elevating means for releasing the succeeding sign from the magazine to deliver the same to the holding means, said sign holding means due to the removal of the sign therefrom and its weight being moved upwardly to receive the released sign.

5. An exhibiting mechanism, having a frame, a sign magazine, means for releasing a single sign at a time, a weight actuated pivoted sign receiving and holding means 110 mounted in the frame to be overbalanced by the received sign, elevating means normally disposed in co-active relation with the sign receiving means, and mechanism for operating the elevating means, and during the operation thereof to release the succeeding 115 sign from the magazine to the displaying means.

6. An exhibiting mechanism, having a frame, a sign magazine, means for releasing a single sign at a time, a weight actuated pivoted sign receiving and holding means mounted in the frame to be overbalanced by the received sign, elevating means normally 120 disposed in co-active relation with the sign receiving means, and mechanism for operating the elevating means, and during the operation thereof to release the succeeding sign from the magazine to the displaying means, said elevating means carrying the 125 130

- sign just removed from the holding means and depositing it within the magazine.
7. A sign exhibiting mechanism, having a frame, a sign magazine, means for releasing a single sign at a time, a weight actuated pivoted sign holding means mounted in the frame to receive the released sign and be overbalanced by the received sign, elevating means normally disposed in co-active relation to the sign receiving means, and mechanism for operating the elevating means and sign releasing means, the elevating means carrying the sign beyond the magazine previous to the actuation of the releasing means.
- 15 8. A sign exhibiting mechanism, having a frame, a sign magazine, means for releasing a single sign at a time, a weight actuated pivoted sign holding means mounted in the frame to receive the released sign and be overbalanced by the received sign, elevating means normally disposed in co-active relation to the sign receiving means, mechanism for operating the elevating means and sign releasing means, the elevating means carrying the sign beyond the magazine previous to the actuation of the releasing means.
- 20 9. A sign exhibiting mechanism, having a frame, a magazine, means disposed at the outlet end of the magazine for ejecting and releasing a single sign at a time, a sign depressed and weight elevated sign receiving and displaying means disposed to receive the ejected sign from the magazine, sign elevating means normally disposed in co-active relation with the sign receiving means, and mechanism for operating the elevating mechanism and sign ejecting means.
- 25 10. A sign exhibiting mechanism, having a frame, a magazine, means disposed at the outlet end of the magazine for ejecting and releasing a single sign at a time, a sign depressed and weight elevated sign receiving and displaying means disposed to receive the ejected sign from the magazine, sign elevating means normally disposed in co-active relation with the sign receiving means, and mechanism for operating the elevating mechanism and sign ejecting means, said elevating mechanism being disposed to carry the sign from receiving and exposing position and to deliver the same to the magazine.
- 30 11. A sign exhibiting mechanism, having a frame, a magazine, means disposed at the outlet end of the magazine for ejecting and releasing a single sign at a time, a sign depressed and weight elevated sign receiving and displaying means disposed to receive the ejected sign from the magazine, sign elevating means normally disposed in co-active relation with the sign receiving means,
- 35 mechanism for operating the elevating mechanism and sign ejecting means, and a sign retarding means disposed to be actuated by the elevating means to receive the sign from the elevating means before delivery to the magazine.
- 40 12. A sign exhibiting mechanism, having a frame, the upper edges of which are inclined to form a gravity guide for the sign, a sign magazine at the lower end of the frame, means for releasing and ejecting a single sign at a time from the magazine, a sign overbalanced and weight raised means for receiving the sign after ejection and disposing the same as a pendant exteriorly of the frame, and means for elevating the sign after exhibition and depositing the same upon the inclined edges of the frame for delivery to the magazine by gravity.
- 45 13. A sign exhibiting mechanism, having a frame, the upper edges of which are inclined to form a gravity guide for the sign, a sign magazine at the lower end of the frame, means for releasing and ejecting a single sign at a time from the magazine, a sign overbalanced and weight raised means for receiving the sign after ejection and disposing the same as a pendant exteriorly of the frame, a pair of pivotal arms provided with sign engaging means disposed in co-active relation with the sign receiving and exhibiting means, and means for actuating said arms to remove the exhibited sign from the receiving and exhibiting means and for delivering the sign to the inclined edges of the frame to be fed to the magazine by gravity.
- 50 14. A sign exhibiting mechanism, having a base, a frame mounted thereon, a sign magazine having two inclined plates disposed to receive the sign, means for ejecting and releasing a single sign at a time from the magazine, a pivoted frame mounted in the main frame and disposed to co-act with the ejecting means of the magazine to receive a single sign at a time and dispose the same as a pendant, means for removing the sign from the pivoted frame and delivering the same upon the inclined edges of the magazine, and means for operating the ejecting and releasing means and the elevating means.
- 55 15. A sign exhibiting mechanism, having a frame, the upper edges of which are inclined to form a gravity guide for the sign, a sign magazine at the lower end of the frame, means for releasing and ejecting a single sign at a time from the magazine, a sign overbalanced and weight raised means for receiving the sign after ejection and disposing the same as a pendant exteriorly of the frame, a pair of pivoted arms provided with sign engaging means disposed in co-active relation with the sign receiving and exhibiting means, another pivoted frame

constituting the sign elevator disposed to describe the arc of a circle within the pivoted sign exhibiting frame, means carried thereby for engaging the sign during exhibiting position, and a mechanism for elevating said last pivoted frame to remove the sign from the pivoted frame and deliver the same to the magazine and for ejecting and releasing the next sign to be exhibited from the magazine.

16. A sign exhibiting mechanism, having a base provided with a slot in one end thereof, a frame carried by the base, a magazine carried by the frame, means for releasing and ejecting a single sign at a time from the magazine, a weight actuated pivoted

sign receiving and holding means mounted in the frame and for receiving the ejected sign and for projecting the same through the slot of the base and below the base, 20 means for removing and elevating the sign from the receiving means and delivering the same to the magazine, and a single mechanism for actuating the sign ejecting and elevating means.

25 In testimony that I claim the foregoing as my own, I have hereto affixed my signature in the presence of two witnesses.

CLARENCE M. EVELETH.

Witnesses:

C. F. WAUZAW,
N. GANSON.
